UNITED STATES PATENT OFFICE.

ERNEST N. LIVERMORE, OF PORT TOWNSEND, WASHINGTON.

DESIGN FOR A MANDOLIN.

SPECIFICATION forming part of Design No. 26,424, dated December 22, 1896.

Application filed October 31, 1896. Serial No. 610,764. Term of patent 14 years.

To all whom it may concern:

Be it known that I, ERNEST N. LIVERMORE, a citizen of the United States of America, residing at Port Townsend, in the county of Jefferson and State of Washington, have invented a certain new and useful Design for the Shape of a Mandolin, of which the following is a specification, reference being had therein to the accompanying drawing.

10 This invention relates to designs for mandolins and mandolas, which consist in the shape or configuration to be hereinafter fully shown, described, and claimed.

15 In the drawing accompanying this application I have shown a perspective view of my design.

20 In the drawing, 1 denotes the body of a mandolin, the bottom of which is of ordinary construction. The upper or top contour on

where the finger-board is attached. The opposite side is curved from the end to a point 2, from whence the outer line of an arm 3 joins the body. This arm curves slightly and extends up to and connects with the head of 25 the finger-board. The inner contour of the arm is approximately parallel with the outer until it merges with the body of the mandolin at a point 4, as shown.

Having fully described my invention, what 30 I claim as new, and desire to secure by Letters Patent, is—

The design for a mandolin, substantially as herein shown and described.

35 In testimony whereof I affix my signature in presence of two witnesses.

ERNEST N. LIVERMORE.
